DESIGN FOR A VACUUM CLEANER

Tord Erik Daniel Bilde, Stockholm, Sweden, assignor to Electrolux Corporation, Dover, Del., a corporation of Delaware

Application October 4, 1940, Serial No. 95,636
In Sweden July 17, 1940

Term of patent 14 years

To all whom it may concern:

Be it known that I, Tord Erik Daniel Bilde, a subject of the King of Sweden and a resident of Stockholm, Sweden, have invented a new, original, and ornamental Design for Vacuum Cleaners, of which the following is a specification, reference being had to the accompanying drawings forming a part thereof and of which:

Fig. 1 is a perspective side view of a vacuum cleaner showing my new design;

Fig. 2 is a perspective view of the opposite side of the same;

Fig. 3 is a perspective view corresponding to that shown in Figure 1 but in which the hoop,

normally keeping the front cover of the cleaner in position is swung into a non-operative position, and said front cover is placed beside the cleaner casing;

Fig. 4 is an end view of the vacuum cleaner looking from the left of the view shown in Figure 1, and

Fig. 5 is an end view of the vacuum cleaner looking from the left of the view shown in Figure 2.

I claim:

The ornamental design for a vacuum cleaner, as shown and described.

TORD ERIK DANIEL BILDE.
